UNITED STATES PATENT OFFICE.

HERBERT LEGGETT, OF KANSAS CITY, MISSOURI.

VALVE-GRINDING MACHINE.

1,246,120,

Specification of Letters Patent. Patented Nov. 13, 1917.

Application filed December 11, 1916. Serial No. 136,353.

To all whom it may concern:

Be it known that I, HERBERT LEGGETT, a citizen of the United States, residing at Kansas City, in the county of Jackson and 5 State of Missouri, have invented certain new and useful Improvements in Valve-Grinding Machines, of which the following is a specification.

The present invention relates to valve 10 grinders of the portable, power driven type, particularly adapted for use in grinding valves of internal combustion engines, and one object is to provide a compact, simple and comparatively inexpensive device which 15 will grind the valve into its seat with the greatest efficiency and despatch.

Other objects of the invention will herein-after appear, and in order that said invention may be fully understood, reference will 20 now be made to the accompanying drawing, in which:

Figure 1 is a broken, side elevation, partly in section of the device in operative engagement with the valve of an internal combustion 25 engine.

Fig. 2 is a detail, plan view of the gearing whereby motion is transmitted from the electric motor of the device to the engine valve.

Fig. 3 is similar to Fig. 2, excepting that 30 the oscillatory cam lever constituting a part of the gearing is removed.

Fig. 4 is an inverted, plan view of the parts disclosed by Fig. 2.

Fig. 5 is a plan view of a modified form 35 of gearing from that disclosed by Fig. 2.

In carrying out the invention, I employ a case embodying a cylindrical shell 1, and caps 2 and 3 closing the ends of said shell. The upper cap 2 has an upwardly-extending 40 handle 4 provided with a central bore to accommodate the switch A and circuit wires B communicating with an electric motor 5 in the case. The outer ends of the circuit wires B, are preferably, provided with a 45 plug (not shown) adapted to be removably-connected to a suitable source of current. The electric motor 5 is provided with a shaft 6 adapted to be driven continuously in one direction and provided with a fixedly-mount- 50 ed pinion 8, having a step bearing 9 in the counterbore of a main shaft 11, journaled in an extension 12 on the lower side of the cap 3.

The lower end of the main shaft 11 is 55 provided with a bit 14, for engagement with

the motor valve C, for the purpose of grinding the same and the valve seat C'. The upper end of the main shaft 11 is provided with a fixedly-mounted, oscillatory cam lever 16 driven in opposite directions by pinions 60 17 and 18, having wrist-pins 19 and 20, respectively, for imparting an oscillatory movement to said cam lever 16.

The gears 17 and 18 are mounted upon 65 stub shafts 22 and 23, respectively, projecting upwardly from a disk 25 loosely-mounted upon the main shaft 11, which has a shoulder 28 whereby it is suspended from said disk 25. The gear 17 intermeshes with the pinion 8 whereby it is driven and also intermeshes with the gear 18 which it drives in an opposite direction thereto. The gears 70 17 and 18 rotate upon their respective axes and are also driven in a circle around the pinion 8, carrying therewith the disk or 75 floating member 25.

29 designates a weight, which in conjunction with the disk 25, to which it is connected by pin-and-slot connections 30, constitutes a rotatable support device forming 80 an important feature of the invention.

The operation of the motor imparts rotation to the power transmission wheels 17 and 18, which wheels through their respective wrist pins and the rotatable support on 85 which they are journaled, effect oscillating and intermittent progressive movement in one direction of the cam lever and hence of the valve. Assuming that the pinion 8 is driven continuously to the right, it will be 90 apparent that the transmission wheels will rotate around their respective axes, and that one of them because it is located nearer the axis of the cam lever than the other, tends to swing said lever the greater distance. To 95 compensate for this, the rotatable support, at a point in the swinging movement of the cam lever, under the pressure applied by wheel 17, will offer less resistance to rotation than is offered by the cam lever and consequently will rotate in the same direction as the pinion until the actuating transmission wheel passes out of engagement with the lever and the other transmission wheel engages the lever and reverses the swing movement thereof. It will thus be seen that the floating support advances intermittently or step by step, making one step for each complete oscillation or back and forth movement of the lever, the advance of the float 100 105 110

ing weight and the consequent planetary movement of the transmission wheels around the pinion 8, effecting corresponding advance or progressive movement of the cam lever and tool-carrying shaft and hence insuring that each oscillatory movement of the valve shall begin at a different point, and thus guard against scoring of the valve and valve seat. It will be understood that the intermittent progressive movements of the tool-carrying shaft will vary in extent according to the resistance encountered, and that the reaction incident to the advance movement or stroke of the cam lever as well as the reverse movement thereof, is yieldingly resisted by the rotative support, which thus acts not only as a member for shifting the transmission wheel centers and thereby rotatably adjusting the valve upon its seat for each oscillation thereof, but also acts as a shock absorber and consequently eliminates all danger of injury to the operative parts of the device, and it will be apparent that the reactions incident to both strokes of the cam lever are absorbed more readily because the inertia of the disk and wheel will be separately overcome.

For certain constructive reasons, I prefer the double actuating gearing 17 and 18 as shown in Fig. 2, but substantially the same results may be accomplished by the internal cam as shown in the modified form, Fig. 5.

In said modified form, the construction and operation of the parts are similar to that in the preferred form, except that by employing an internal cam lever 16^a one wrist-pin 20^a, is all that is required to oscillate said cam lever. By making the slot 16^b slightly at an angle to the longitudinal axis of the cam lever 16^a, wrist-pin 20^a remains in contact longer with the side 16^c of the slot than with the side 16^d. In this connection, it will be noted that the pressure of the pin against the outer end of the lever finds less resistance to movement by the support than is offered by the lever itself and hence the support turns in the same direction as the pinion and advances the gear center. The advance movement, which is repeated upon each corresponding operation of the wrist pin, is but slight before the continued rotation of the gear wheel places the preponderating pressure on the cam lever and imparts reverse oscillation to the same and to the shaft. As the remainder of the elements bear similar numerals with exponents to the corresponding parts of the preferred form, further description of the modified form is deemed unnecessary.

Having thus described my invention, what I claim and desire to secure by Letters Patent, is:

1. In a valve grinding machine, a drive gear, a valve-actuating shaft, a laterally extending lever fixed to said shaft, a support

mounted for free oscillation about said shaft, and means carried by the support and driven by said gear to oscillate the lever and through reaction oscillate said support.

2. In a valve grinding machine, a drive gear, a valve-actuating shaft, a laterally extending lever fixed to said shaft, a support mounted for free oscillation about said shaft, means carried by the support and driven by said gear to oscillate the lever and through reaction oscillate said support, and a weight member having play connection with said support.

3. In a valve grinding machine, a tool-actuating shaft, means for rotating continuously in one direction, a floating support forming a journal for said rotating means, and means acting through the rotation of said first-named means to oscillate the shaft and reacting to the resistance of the latter to oscillate the said floating support.

4. In a valve grinding machine, a tool-actuating shaft, means for rotating continuously in one direction, a floating support fitting around said shaft and forming a journal for said rotating means, and means acting through the rotation of said first-named means to oscillate the shaft and reacting under the resistance of the latter to oscillate the said floating support about said shaft.

5. In a valve grinding machine, a drive pinion, a tool-actuating shaft, means driven continuously in one direction by said drive pinion, a floating support forming a journal for said driven means, and means acting through the rotation of said driven means to oscillate the shaft and reacting under resistance of the latter to oscillate the said floating support.

6. In a valve grinding machine, a tool-actuating shaft, means for rotating continuously in one direction, a floating support forming a journal for said rotating means, means acting through the rotation of said first-named means to oscillate the shaft and reacting to the resistance of the latter to oscillate the said floating support, and a weight movable with said support and having a play connection therewith.

7. In a valve grinding machine, a gear pinion, a shaft, a lever projecting laterally from said shaft and provided with a cam slot, a wheel intergeared with said pinion, a pin projecting from said wheel into said cam slot, and a device forming a journal support for said wheel and mounted for oscillatory action to periodically shift the position of said wheel about the drive pinion without disengaging it from the latter.

8. In a valve grinding machine, a casing, a valve-operating shaft journaled in and projecting from the casing, a drive shaft within the casing and aligned with the first-named shaft, a gear wheel driven continu-

ously in one direction by said drive shaft, a lever projecting laterally from said valve-operating shaft, a pin-and-slot connection between said gear wheel and lever whereby rotation of the former effects oscillation of the latter, and a support mounted to turn freely in both directions and forming a journal support for said gear wheel to shift

the position of the latter without disengaging it from said drive shaft.

In testimony whereof I affix my signature in the presence of two witnesses.

HERBERT LEGGETT.
